BASE FOR POST TOP OUTDOOR LUMINAIRES

Bernard R. Stockwell, Sunbury, Ohio, assignor to Holophane Company, Inc., New York, N.Y., a corporation of Delaware

Filed Nov. 9, 1966, Ser. No. 4,591

Term of patent 14 years

(Cl. D48—31)

FIG. 1 is a front perspective view of a base for post top outdoor luminaires, showing my new design;

FIG. 2 is a front elevational view thereof;

FIG. 3 is a right-side elevational view thereof, which appears the same as the left-side elevational view thereof;

FIG. 4 is a rear elevational view thereof; and

FIG. 5 is a bottom view thereof.

The dominant features of my design reside in the portions shown in full lines. The broken line showing of a support pole and luminaire head is for illustrative purposes only and has been fragmentarily shown throughout for convenience of illustration.

I claim:

The ornamental design for a base for post top outdoor luminaires, substantially as shown and described.
